COMMUNICATION SYSTEM

Harry J. Nichols and Henry L. Tholstrup, Dayton, Ohio, assignors, by direct and mesne assignments, to International Business Machines Corporation, New York, N. Y., a corporation of New York

Application February 23, 1935, Serial No. 7,674

6 Claims. (Cl. 178—66)

This invention relates to communication systems, and particularly to carrier telegraph systems.

It is the principal object of the invention to provide a very satisfactory carrier communication system making use of simple and economical apparatus.

A further object is to provide a carrier system having a minimum of steps or links in the system.

10 A further object is to provide a carrier system particularly adapted to telegraph systems utilizing signals of uniform duration but of different characteristics.

15 A further object is to provide a carrier system in which frequencies are generated, amplified, and the like in groups, each group being handled in such manner as to obtain compensation of certain variations in the relations between the signals of the several frequencies.

20 A further object is to provide a carrier system particularly adapted to simultaneous telephonic and telegraphic communication over the same circuit.

25 Other objects and features will be in part obvious and in part hereafter pointed out in connection with the following description, the accompanying drawings, and the appended claims.

In the drawings:—

Fig. 1 shows in schematic representation a preferred form of sending circuit illustrating one aspect of the invention;

Fig. 2 shows one form of receiving circuit according to the invention;

Fig. 3 shows another form of receiving circuit according to the invention; and

Fig. 4 shows a combined sending and receiving arrangement embodying the circuits of Figs. 1 and 3.

In the several figures, like characters represent like parts.

Referring now to Fig. 1, oscillator tube 16 is connected to the oscillator circuit, and the oscillator tube type

preferably of the twin-triode vacuum tube type being provided with two grids 11 and 12, two anodes 21, 22, and a common thermionic cathode 13 all mounted in an evacuated envelope 14 in well known manner. Power for tube T₀ and the other tubes employed in the various circuits is obtained from a rectifier and filter unit 15 as indicated or from any other suitable source. The

50 cated, or from any other source, a voltage divider of unit 15 is provided with the proper sections; as for example 15a, 15b, 15c, or 55 is suitably tapped to provide the proper potentials to the various circuits of the arrangement. Oscillator tube T₀ is provided with two tuned oscillator circuits of known type, one circuit designated by reference numeral 11' being associated with grid 11, while similar circuit 12' is associated with grid 12. Inductively coupled with these circuits are feed-back circuits 21', and 22', associated with anodes 21 and 22 respectively forming

ing oscillation transformers OT₁ and OT₂, respectively. Oscillator circuit 11' is tuned to a particular frequency f_1 while oscillator circuit 12' is tuned to a different frequency f_2 . These are known as the channel frequencies, and in cases where simultaneous telephone and telegraph communication are to be provided over the same circuit, these frequencies are preferably chosen in the range just above the usual audible telephonic frequencies, as for example in the range between ten and twenty kilocycles. Where telephonic communication is not involved, the frequencies are advantageously chosen in the audible range since following well known laws, the lower frequencies are more efficiently transmitted over wire circuits. The invention is not, of course, restricted to any particular frequencies or frequency ranges, nor is it restricted to the provision of two channel frequencies and circuits, as more may be provided if desired.

Grids 11 and 12 are normally held at a negative bias by section 15b of the voltage divider, the bias being sufficient to prevent oscillation. The normal bias is applied through resistors R₁₁, R₁₂, while by-pass capacitors C', C'' offer a low impedance return of the oscillating grid currents to cathode. 25

The keying equipment is connected across the grid-cathode circuits of oscillator tube T_0 . Thus, for example, the circuit including key K_1 , resistor R_{11} , and battery B may be regarded as the sending loop of channel one, while the circuit including key K_2 , resistor R_{12} and battery B may be regarded as the sending loop of channel two. Both oscillation circuits are coupled to the line by suitable means such as line transformer Tr_5 . Blocking capacitor C_5 is provided to prevent direct current from the line saturating transformer Tr_5 , but is not essential on lines where stray currents are not likely to occur. The sending circuit, consisting of the secondary of Tr_5 and C_5 in series therewith is preferably bridged across the line head of telephone instruments when used. Suitable means, such as choke L_5 , is preferably connected in series with the telephone instruments for the purpose of impeding the passage of carrier currents in that direction while permitting the passage of voice currents to the telephone instruments.

The operation of the circuit shown in Fig. 1 is 50 as follows:—Normally oscillator tube T_0 is prevented from oscillating by reason of the negative bias on its grids. Assume that the key K_1 is closed, completing the sending loop circuit. Then current from battery B flows through K_1 and R_{11} 55 and return via the grounded frame, setting up a voltage across R_{11} opposing the bias voltage and raising the potential of grid 11 sufficiently to cause T_0 to build up oscillations in the circuit 11' associated with grid 11. Oscillations of fre- 60

quency f_1 are then transferred to the line via line transformer $Tr5$. As soon as the key is released the original bias on grid 11 is returned, and the oscillations are promptly stopped. Thus a train 5 of waves of frequency f_1 is transmitted over the line so long as key K_1 is held down, and such carrier signals represent the signal pulses in the sending loop as regards time and duration. Assuming key K_2 to be depressed, the action is similar 10 except that the potential of grid 12 is raised positively and carrier signals of frequency f_2 are transmitted to the line.

It should be observed that the arrangement herein shown eliminates the need for an amplifying tube, with a consequent saving in apparatus although such amplifying means as desired may be used. It also presents a novel method of "keying" carrier generating apparatus. Furthermore, since the same oscillator tube generates 20 a plurality of frequencies, there is an inherent compensation of variations likely to occur were the frequencies generated by separate tubes. For example, a common cathode and a common atmosphere for the plural elements 25 of the tube are conducive to uniformity of emission and space currents. As the tube ages, the constants of the tube circuits are affected in the same degree, hence the power ratio of the oscillating currents tends to remain balanced, thus maintaining a uniform ratio of 30 the signals. The tuning and balancing of the circuits is facilitated by the uniformity of the characteristics of the plural tube circuits. There is also a saving in power, a saving in space and 35 in associated parts.

Referring now to Fig. 2, representing one form of receiving arrangement, the receiving circuit 20 is coupled to the line by line transformer $Tr5$ in the same manner as in the previous figure or by other suitable means. Likewise, inductance $L5$ offers a high impedance to the carrier signals in the direction of the telephone instruments with relatively minor attenuation of the voice currents. The receiving circuit 40 20 is divided into two branches 20' and 20" tuned to frequencies f_1 and f_2 by series combinations of capacity and inductance, C_1 , L_1 and C_2 , L_2 , respectively. The primaries of transformers $Tr1$ and $Tr2$ are included in branch 45 circuits 20' and 20", and the secondary circuits of these transformers are tuned to frequencies f_1 , and f_2 by capacitors C_3 and C_4 respectively. Transformers $Tr1$ and $Tr2$ couple the tuned branch circuits to the grids of electronic relays 50 T_1 and T_2 as shown. The L/C ratio or ratio of inductance to capacity of the tuned circuits including C_3 and C_4 should preferably be small in order that the full resonant response of the tuned circuits will be somewhat delayed. This 55 counteracts the tendency of transient impulses to "trip" T_1 and T_2 .

Electronic signal translating devices comprising relays T_1 and T_2 are preferably of the well known triode gas-discharge tube type in which the grid "trips" or ionizes the tube permitting a comparatively large ionization current to flow in the anode-cathode circuit thereof. After ionization, the grid loses control and is ineffective to terminate the discharge until the anode potential is reduced substantially to zero. Hence deionizing or cut-off means additional to the grid are provided when direct current is used to supply the anode circuit. Any suitable means may be used, such means being indicated by reference numeral 25. For example, a cut-off relay

may be used in the position of 25 when the tubes are used alternately, to effect deionization of the tube or interruption of the circuit after a brief interval of operation, thus serving both tubes, or other known means may be used. Resistors R_1 , 5 R_2 serve to limit the grid current upon ionization of their associated relays, while resistors R_3 , R_4 represent the load resistances of T_1 and T_2 respectively. Relays L_3 , L_4 may represent the receiving relays for two channels, two printer actuating magnets, or any other translating means by which the telegraphic signals are recorded or rendered intelligible. Relays T_1 and T_2 are conveniently supplied with energy by rectifier unit 10 15 or from any other suitable source.

The operation of the arrangement of Fig. 2 is as follows: Assume that a train of carrier waves of frequency f_1 is received from the line. Owing to the tuned filter arrangement L_1 , C_1 in branch circuit 20', this branch offers a markedly lower impedance to the signal train than does branch 20". Hence the voltage which appears across the secondary of $Tr1$ is considerably higher than that across the secondary of $Tr2$. Furthermore the secondary of $Tr1$ being tuned 20 to frequency f_1 , while the secondary of $Tr2$ is tuned to frequency f_2 , a further frequency selective effect is obtained. For example, under suitable conditions, for signals of frequency f_1 the voltage ratio of the potential applied to the grid of T_1 as compared to the potential applied to the grid of T_2 may be 10 to 1, while a like ratio favorable to T_2 may be obtained for signals of frequency f_2 . Thus by suitable choice of the operating conditions for T_1 and T_2 , following well 30 known practice, T_1 will be exclusively tripped by signals of frequency f_1 , while T_2 will be exclusively tripped by signals of frequency f_2 .

Assuming that T_1 has thus been tripped, a pulse of current flows (following the ordinary convention) from positive source via cut-off device 25 to the anode of T_1 , thence by space current to cathode, through resistor R_3 to frame and return to source. The current through resistor R_3 causes a potential drop across same, hence 40 part current (in such amount as is desired) is diverted through the winding of relay L_3 energizing same. After an interval determined by cut-off device 25, the potential across the anode and cathode of T_1 is reduced substantially to zero, the potential being held down long enough to permit the grid of T_1 to regain control, thus 45 effecting the de-ionization of T_1 .

In similar manner, upon the reception of a train of waves of frequency f_2 , T_2 is ionized, relay 50 L_4 is energized and cut-off device 25 causes the deionization of T_2 thus restoring the circuit to normal condition.

It should be noted that the cut-off device operates to effect deionization after a definite, 55 predetermined interval, hence the translating devices are energized for the same duration by all signals of amplitude sufficient to ionize the electronic relays. The invention is thus particularly suitable to equal signal systems, and in such systems has the practical advantage of 60 providing reliable operating impulses even though the received signals may be clipped or mutilated.

The arrangement here shown is very desirable in that among other advantages, it eliminates 65 the need for a detector and/or amplifying tube, the electron relays which perform the usual function of a line relay being actuated directly by the incoming signals. It is characterized by 70 its simplicity and advantageous use of electron 75

relays. In addition to the selective action of the tuned receiving circuits, further selective action is obtained by the novel method of selective tuning of the electron relay input circuits.

5 Referring now to Fig. 3 which shows another form of receiving arrangement in accordance with the invention, selection as to frequency is accomplished in steps, the first of which occurs in the coupling circuits of tube T_0 which here 10 functions as a signal amplifying tube. The arrangement shown is particularly suitable for use on lines where the attenuation is considerable and/or where the channel frequencies are narrowly spaced. The secondary circuit 20 of line 15 transformer Tr_5 has two branch circuits 20', 20'' including coupling coils 21', 22' of transformers OT_1 and OT_2 , these branch circuits being selectively tuned to frequencies f_1 and f_2 by suitable means such as filter arrangements S_1, L_1 and C_2, L_2 . 20 The secondaries of OT_1 and OT_2 are also tuned to frequencies f_1 and f_2 respectively, and apply potential variations corresponding to the carrier signals to grids 11 and 12 of tube T_0 . The primaries of transformers Tr_1 and Tr_2 are included 25 in plate circuits 31 and 32 associated with plates 21 and 22 respectively. The remainder of the arrangement is as described in connection with Fig. 2.

The operation is as follows:—Carrier signals 30 from the line are transferred by line transformer Tr_5 to branch circuits 20' and 20'', but in unequal degree depending upon the carrier frequency, as for example signals of frequency f_1 are offered a low impedance path by filter combination L_1, C_1 and a high impedance path by filter combination L_2, C_2 , hence the major portion of the energy flows in circuit 20'. For signals of frequency f_2 the reverse holds. Further selective action occurs in tuned circuits 40 11' and 12' improving the voltage ratio of the potentials applied to grids 11 and 12. Tube T_0 amplifies the signals, which are applied with augmented amplitude to the primaries of transformers Tr_1 and Tr_2 . With proper operating 45 conditions, T_1 will thus be tripped by f_1 signals, and T_2 by f_2 signals, producing selective operation of translating devices L_3 and L_4 .

This arrangement is characterized by its high selection ratio, its ability to function reliably on 50 weak signals, its economy of apparatus, and the inherent compensatory features of the twin amplifying tube employed.

It should be noted that amplifying tube T_0 has the beneficial effect of increasing the selection 55 margin. As is well known, electron relays such as T_1 and T_2 here employed are tripped by a certain critical value of potential. For example, let it be assumed that each tube can be tripped by a peak potential of twenty volts applied to the 60 primaries of Tr_1 and Tr_2 . Let it further be assumed that the selection ratio due to tuned circuits L_1, C_1 , and L_2, C_2 and tuned transformers OT_1 and OT_2 is ten to one, and that the effective 65 amplification factor of T_0 is five. Then if the peak voltage on grid 11 due to a f_1 signal is 10 volts, that on grid 12 will be one volt, giving a selection margin of nine volts. After amplification by tube T_0 , these peak voltages become 50 70 volts and 5 volts respectively, giving a selection margin of 45 volts. This voltage difference, applied to T_1 and T_2 by transformers Tr_1 and Tr_2 , provides a substantial operating margin for selection purposes. It is to be understood that the voltage values cited in the example are for illustrative purposes, and in practice reliable selec- 75

tive action can be obtained with comparatively feeble carrier signals, and widely varying selective ratios.

Referring now to Fig. 4, a combined sending and receiving arrangement is shown which is particularly adapted to two way systems in which communication is held in one direction or the other, but not simultaneously in both directions. This arrangement represents a combination of those shown in Figs. 1 and 3.

Suitable switching means, designated by S, S_1, S_2, S_3 , are provided to change the circuits at will from sending to receiving condition. The switches are shown at convenient places in the diagram, but in practice are conveniently grouped 10 in a single multiple switch. It is assumed that when the switch tongues are moved to the right, the circuits are in sending condition and when moved to the left are in receiving condition. Assuming first that sending conditions are to be 15 established, all switch tongues are to be considered as being to the right. Switch S then applies positive potential to plate 21 via lead 20, primary of Tr_5 , branch 20' and coil 21', via switch S_1 , and thence to plate 21; and to plate 25 22 through the circuit including the primary of Tr_5 , thence through branch 20'' and coil 22', via switch S_2 to plate 22. Switch S_3 connects the sending device, such as printed 34, across grid resistor R_{11} via lead 41, and across grid resistor R_{12} via lead 42. A printer which has been found to give very satisfactory results is that disclosed in our copending application Serial No. 738,833, filed August 7, 1934.

The sending operation is the same as described 35 in connection with Fig. 1, except that printer 34 functions in the same manner as but replaces the keying arrangement comprising K_1, K_2 , and B of Fig. 1. Briefly, one portion of the printer circuits is associated with OT_1 and the other portion with OT_2 . When one of the printer keys is operated, the tube T_0 is placed in oscillation at the selected frequency, f_1 or f_2 , and for the proper duration and at the proper time in accordance with the particular key operated, a corresponding signal being sent over the line.

Assuming next that receiving conditions are to be established, all switch tongues are moved to the left. Switch S connects lead 20 to the mid point between C_1, C_2 ; switch S_1 connects 50 plate 21 to lead 31, and coil 21' to L_1 ; while switch S_2 connects plate 22 to lead 32 and coil 22' to L_2 , thus completing the signal circuits as described above in connection with Fig. 3. Switch S_3 connects printer 34 to leads 51 and 55 52 which are included in the output circuits of electron relays T_1 and T_2 .

The receiving operation is the same as that described in connection with Fig. 3, except that printer 34 functions in the same manner as but 60 replaces the translating devices L_3, L_4 of Fig. 3. Thus the signals, distinguished by their frequency, time, and/or duration, are caused to effect the selective operation of the printer and to cause operation of the printer keys corresponding to those at the sending station.

The arrangement is characterized by its dual utility, relative simplicity, and balancing and compensating features.

It will be apparent that the arrangements 70 shown in Figs. 1 and 2 can be combined into a sending-receiving unit in the same general manner as the arrangements of Figs. 1 and 3 have been combined, and in some applications may be preferable to that shown in Fig. 4. The detailed 75

connections for such combination will readily be seen by those skilled in the art, hence further description is not required.

The advantages enumerated, and others un-
5 mentioned, are attributable to the method of handling the channel frequencies in groups, to the use of a multiple tube with balanced elements, to the advantageous use of electron re-
lays in combination with frequency selective cir-
10 cuits, and to the novel arrangements disclosed.

It will be apparent that the invention provides a carrier signalling system which is relatively simple, economical in the use of apparatus, effi-
cient and reliable in action, and which meets in
15 a highly satisfactory manner the manifold and exacting requirements for a system of this type.

While the methods herein described and the forms of apparatus for carrying these methods into effect constitute preferred embodiments of
20 the invention, it is to be understood that the in-
vention is not limited to these precise methods and forms of apparatus, and that changes may be made in either without departing from the scope of the invention which is defined in the
25 appended claims.

What is claimed is:

1. In carrier signalling systems, a carrier fre-
quency selective receiving arrangement comprising
30 a plurality of frequency selective receiving
circuits each tuned to a particular frequency,
a plurality of electron discharge tubes each pro-
vided with a control grid and adapted to be
substantially completely ionized upon the direct
35 application of a signal having a critical value of
potential to its control grid, magnetic coupling
means for coupling said selective receiving cir-
cuits to the grids of said discharge tubes, said
magnetic coupling means being provided with a
40 tuned secondary circuit characterized by an L/C
ratio adapted to retard the resonant response of
said tuned circuit, a plurality of signal translat-
ing means each operatively associated with the
discharge circuit of one of said discharge tubes,
45 a source of direct current for applying operating
potential to said discharge tubes, and discharge
current terminating means associated with said
discharge tubes adapted to produce deioniza-
tion of said discharge tubes.

2. The arrangement specified in claim 1 in
50 which the magnetic coupling means for coupling
the selective tuned receiving circuits to the grids
of the discharge tubes have the grid circuits
tuned to the same frequency as the receiving
circuits.

55 3. A carrier signalling system comprising, in
combination, wave generating means including
an electron tube having a plurality of grid and
anode elements mounted in a common sealed
envelope and including individual circuits con-
60 nected to said elements adapted to generate
oscillations of a plurality of predetermined fre-
quencies, an energy source for said tube, individ-
ual oscillation circuits included in each of
the circuits connected to the grid elements, means
65 coupling the said oscillation circuits to the individ-
ual anode circuits, means included in the grid
circuits for normally conditioning said tube to
inhibit oscillations, keying means in the individ-
ual grid circuits, and means common to said
70 keying means to nullify the said tube condition-
ing means upon operation of any one of the
keying means thereby conditioning the selected

grid circuits to provide for the generation of oscillations of a selected one of said predetermined frequencies as long as the selected keying means remains operated.

4. In a carrier telegraph system a two channel receiving arrangement including, in combination, two selective receiving circuits each tuned to an individual frequency, selective signal translating means, and selective signal amplifying means including an electronic amplifying tube provided with twin control grids connected respectively in said selective receiving circuits and also having twin anodes, said grids and anodes being immersed in a common atmosphere and sealed in a common envelope, two electronic discharge tubes each provided with control grids and adapted to be ionized upon the application of a critical value of potential to their control grids, and individually tuned magnetic coupling means for coupling the anode circuits of said amplifying tube to the control grids of said discharge tubes, said tuned circuit of the magnetic coupling means being characterized by a controlled small L/C ratio adapted to retard the resonant response of said tuned circuit.

5. In carrier signal terminal apparatus adapted to function selectively for sending and receiving, in combination, an electronic discharge device having a plurality of grid and anode elements mounted in a common sealed envelope and including individual circuits connected to said elements, individual tuned circuits included in each of the grid circuits and including means for normally conditioning the device to prevent current flow in the anode circuits, individual keying means included in the said grid circuits and signal translating means controlled by the said anode circuits, positionable switching means to condition selectively the said device and said associated circuits whereby in one position the keying means are effective to initiate selectively carrier signals of predetermined frequencies and in another position condition the same said elements of the device and associated circuits to amplify selectively signals of the aforesaid predetermined frequencies on receiving thereby controlling selectively the operation of the said translating means.

6. In carrier signal terminal apparatus adapted to function selectively for sending and receiving, in combination, signal translating means, selectively tuned electronic relay means adapted to selectively actuate said signal translating means, an electronic discharge device having a plurality of grid and anode elements mounted in a common sealed envelope and including individual circuits connected to said elements, individual tuned circuits and individual keying means included in each of the grid circuits, and positionable switching means to condition selectively the said device and associated element circuits whereby in one position selective operation of the keying means are effective to initiate selectively carrier signals of predetermined frequencies, and in another position condition the same said elements of the device and associated circuits to amplify selectively signals of the aforesaid predetermined frequencies thereby controlling selectively the operation of the said electronic relay means and associated translating means.
